UNITED STATES PATENT OFFICE.

CLAIBORNE W. GOOCH, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,327,319.

Specification of Letters Patent.

Patented Jan. 6, 1920.

Application filed February 15, 1916. Serial No. 78,391.

To all whom it may concern:

Be it known that I, CLAIBORNE W. Gooch, a citizen of the United States, residing at Detroit, in the county of Wayne and State 5 of Michigan, have invented new and useful Improvements in Adding-Machines, of which the following is a specification.

The present invention relates to the key-driven class of adding machines which do 10 not ordinarily have any printing equipment. It is frequently desirable in the carrying on of calculating work through use of machines of this sort, to be able to preserve a grand total of the sums of several series of additions or computations. Ordinarily these 15 machines have a single set of registering wheels and when so equipped there is no way of preserving a registration of a sum or total while another is being accumulated. 20 The purpose of my present invention is to enlarge the capacity of machines of this class by providing an additional set of accumulating wheels and so relating them to the key-driven actuating mechanism or to the 25 regular set of wheels, that the registration of a sum or total may be preserved upon this additional set of wheels while the regular set is returned to zero for the commencement of a new series of registering operations, the 30 sum total of which may be added to that preserved upon the additional set of wheels. In carrying out my invention I provide for using the machine in the ordinary way, as a single accumulator machine, and I provide 35 for bringing into play the additional set of wheels at the will of the operator in order that registrations may be made simultaneously upon the two sets of wheels, and I further provide for resetting the regular set 40 of wheels to zero without affecting the additional set of wheels. Provision is also made for simultaneously resetting both sets of wheels to zero.

In the construction here shown the additional set of numeral wheels is located at the rear just beyond the keyboard and a set of actuating gear segments is so arranged as to be operable at will by the same key-driven 45 actuators which drive the similar gear segments through which motion is transmitted to the regular set of numeral wheels at the front of the machine. A special key is provided whose depression results in coupling the extra set of gear segments to said actuators,

The zeroizing of the regular set of wheels involves forward rotation of them collectively and independently of any movement of the column actuators, the said wheels being thus independently advanced from various registering positions,—the units wheel to zero and the higher order wheels to the 9 position, and the operation being completed by transmission of a carrying impulse across the series of wheels. I make provision for 60 similarly zeroizing the additional set of wheels at the rear of the machine, and in this connection I provide another special key whose depression operates to couple the rear zeroizing mechanism to the zeroizing 65 actuator which appears in the form of the usual hand lever at the right-hand side of the machine.

Referring to the drawings which accompany and form part of this specification, 75 Figure 1 represents in left-side elevation, and somewhat condensed longitudinally, a machine embodying my present invention, the casing thereof being omitted and portions of the supporting frame work being 80 broken away and various supporting shafts and rods being correspondingly shown in section; Fig. 2 represents some of the same parts under different conditions produced by depression of the special key first above referred to, and depression of an amount key thereafter; Fig. 3 represents a top plan view of the machine with side frame pieces partly 85 in section and the keyboard broken away; Fig. 4 represents the machine in right-side 90 elevation with the outside frame piece for the most part omitted; Fig. 5 is a skeletonized perspective of the parts which have especially to do with the carrying out of the present invention; Fig. 6 is a fragmentary 95 left-side elevation illustrating certain interlocking devices in operation; Fig. 7 is a right side elevation corresponding with Fig. 4 and illustrating the zeroizing mechanism in 100 operation as to both accumulators.

Inasmuch as the machine here shown, in so far as it constitutes a key-driven calculator of single accumulation capacity, is identical with that illustrated and described in detail in the prior Patent No. 1,243,839 105 issued Oct. 23, 1917, upon the invention of Allen A. Horton, this reference to that patent makes unnecessary a detailed description in the present specification of what the accompanying drawings show in that respect. 110

In aid of a ready comparison, however, I have applied to identical parts the same reference characters used in said patent.

In carrying out the present invention the 5 casing of the machine is extended at the rear and so are the various supporting frame plates, and an accumulating mechanism is mounted in the upper portion of this extended casing and framework, so that the 10 numeral wheels A^x may easily be read through sight openings in the cover piece of this part of the casing. This additional accumulating mechanism is a substantial duplicate of that at the front of the machine. The gear segments E^x for driving this rear set of wheels are journaled upon the same cross-rod z which supports the bell 15 crank levers B . The latter are just such members of the key-driven actuating system 20 as found in the aforesaid patent, the same being held normally rearward by the power springs B' and adapted to be swung forward by depression of the numbered keys F . Each of said segments is mounted immediately adjacent one of the bell crank levers B , as shown most clearly in Fig. 5, and 25 is offset so as to be brought into the same vertical plane. Normally the gear segments E^x are held rearward by springs 30 against a rock shaft 31, and abutment lugs b on the bell crank levers B meet similar lugs e on the segments. Each of the latter carries a 30 coupling hook 32, pivoted on the left-hand side of the segment at the upper forward corner thereof, and the associated bell crank lever B has a laterally projecting stud b' with which the hook is adapted to engage. A spring 33 which connects a rear arm of the hook with a stud 34 on the segment, 35 tends to bring about engagement between the hook and the stud. It is, however, normally restrained from so doing as are all of the corresponding springs on the other segments, by a gang of arms or fingers 35 fastened to the rock shaft 31. The normal 40 condition is illustrated in Figs. 1 and 5, wherein it will be observed that these fingers are engaged with laterally-turned end-portions of the latches. Under these conditions depression of the numbered keys will 45 have no effect upon the rear accumulator but will merely result in turning the wheels of the forward accumulator.

There is secured to the left-hand end of 50 said rock shaft 31 a crank arm 36 and there is journaled upon the frame cross rod z a lever 37 which at its rear end has a slot-and-pin connection with said crank arm and at its forward end is pivotally coupled to 55 the lower end of the stem 38^a of a key 38 which is conveniently located at the left of the keyboard. This constitutes the special key whose depression results in coupling the 60 rear segments E^x with the bell cranks B and thereby causing the rear accumulator to be

operated simultaneously with the front accumulator by depression of amount keys. Thus it will be seen that depression of this key results in rocking forward and downward all of the fingers 35 and thereby permitting the several springs 33 to immediately interlock the hooks 32 with the studs b' , so that when the bell crank levers B are forced forward by depression of the operated keys the said segments will be carried 75 along with them. The key stem 38^a is preferably notched as at 38^b to provide for its being hooked under the keyboard plate to maintain the duplex accumulating state of the machine. A spring 39 applied to the lever 37 normally upholds the said key.

It is desirable to guard against the possibility of simultaneously depressing said key and any amount key, and I therefore provide a simple interlocking arrangement to 85 prohibit any such erroneous manipulation. In the construction of the aforesaid patent an interlocking arrangement is provided between the numbered keys and the zeroizing actuator, which includes a rock shaft 24 and 90 pendent plates 25. I utilize the same rock shaft for effecting the interlock between the amount keys and the "duplex" key. Thus I secure upon the left-hand end of said rock shaft an arm 24^b, which I equip with a stud 95 24^c, and I form integral with the crank arm 36 on rock shaft 31, a cam blade 36^a to cooperate with said stud. Normally the stud is accommodated at the low forward part of the cam blade (Figs. 1 and 5) and of course 100 the latter does not interfere with depression of amount keys. Similarly when the key 38 is fully depressed, the said stud is accommodated at the low rear part of the cam blade. (Fig. 2.) During depression or rise 105 of the said key, the high middle portion of the cam blade wipes past the stud so that during such time the rock shaft 24 blocks the plates 25 in the manner described in said patent, said shaft having been rocked by 110 the camming action of the blade upon the stud 24^c, Fig. 6.

Referring next to the matter of zeroizing, (Figs. 4, 5 and 7). Y' designates a crank arm of the prior construction, and Z' the 115 hand-lever rotatively interlocked with said crank-arm, the latter being operatively connected as usual with a rock shaft X serving to operate devices which lock the gear disks I and operate the levers H , in the manner 120 and with the effect fully described in the aforesaid patent. There is a corresponding rock shaft X^x serving to operate similar devices for zeroizing the rear set of wheels in the same manner, and I provide for the 125 driving of this rock shaft by the hand-lever Z' , the same as the rock shaft X is driven, whenever it is desired to zeroize the rear set of wheels. On the right-hand end of said rock shaft X^x is secured a crank arm 130

which has a slot-and-pin connection with the upper arm of a lever 51 whose lower arm carries a stud occupying an arc-shaped slot at the rear end of a long link 52. The latter 5 extends forward alongside the crank arm Y' and is notched adjacent the same as shown at 52^a. The said crank arm Y' carries a stud y for co-operating with said notch to reciprocate the said link 52. Normally 10 the link is held up with the forward side of the notch clear of the stud as shown in Fig. 4, so that a forward stroke of the crank arm Y' has no effect upon the link. Lowering of the link to interlock it with the stud is accomplished by depression of a special key 15 53 located at the left of the keyboard just in rear of the key 38. The stem 53^a of this key is pivotally connected with an arm 54 fastened to a rock shaft 55 which at its 20 right-hand end carries another arm 56 having a stud 56^a occupying a slot 52^b in the link 52. A spring 57 is applied to the longer arm 54, (Fig. 1) and normally upholds the key 53 and the link 52. Depression of the 25 key swings the rock shaft arm 56 down carrying the link with it and interlocking the latter with the crank arm Y', as shown in Fig. 7, where the condition represented is that obtained when the zeroizing handle 30 is forward. In order to avoid the necessity of maintaining finger pressure upon the key 53 throughout the operation, and also to insure maintenance of the coupling between the link 52 and crank arm Y' 35 throughout the operation, said link is made with a raised portion 52^c to run under the frame stud 19^a when the link starts forward and remains under that stud until the link returns to normal, as shown in Fig. 7.

40 The reason for slotting the rear end of the link 52 is the same as that for connecting the crank arms Y' and X' in the prior construction by the links X² and spring X³. A spring 58, having a corresponding function, connects 45 the stud at the lower end of the lever 51 with a stud 52^d carried by the link 52. The function of the yielding connection between the zeroizing actuator and the zeroizing mechanism of the prior construction, is fully 50 explained in said prior patent, in its relation to the working of those devices which operate to prevent erratic action in zeroizing through too quickly executing a second stroke of the hand lever. Devices of the 55 same sort and performing the same function in the same way, though somewhat changed in form, are employed in connection with the rear accumulator. They appear in Fig. 1 and to facilitate comparison with the old 60 devices, I have applied to them corresponding reference characters with the suffix x. As in the case of the forward accumulator, which is exactly like that shown and described in said prior patent, so in the case 65 of the present rear accumulator, the spring

58 will stretch when the stud W^{2x} encounters the blocking shoulder of the lever 10^x as a result of too speedy execution of a second stroke of the hand lever.

There is illustrated in the present drawings the same interlock between the hand lever and the numeral keys that is shown and described in said prior patent, with a modification made necessary by reason of the before described interlock between the "duplex" key 38 and said numeral keys. Thus the link 22, instead of having merely a pivotal connection with the crank arm 23 on the right hand end of the rock shaft 24, is slotted as shown at 22^a, and the crank arm 80 stud 23^a is connected by a spring 23^c with a stud on a rearward extension of said link 22. This provides for rocking of said shaft 24 independently of the link 22 when the "duplex" key 38 is depressed. 85

Controlling devices for preventing over-rotation of numeral wheels are here shown in connection with both sets of wheels, these devices being the same as those shown and described in my prior Patent No. 1,150,937, 90 issued August 24, 1915. They comprise notched disks A' and co-acting toothed wheels B', the former united with the driving ratchets and the wheels B' being formed integrally with broad pinions B² meshing 95 with the driven gear wheels S. The registering wheels must be freed from the control exercised over them by these devices, whenever zeroizing is to be performed. The said broad pinions are therefore carried upon a 100 laterally shiftable shaft 60, (Fig. 3). For the purpose of shifting the shaft of the forward controlling devices, one of the links X² is equipped with a cam hook 61, (Fig. 4) which embraces said shaft between collars 105 thereon. As clearly shown in Fig. 3, the formation of this hook is such as to shift the said shaft to the left when the hand lever Z' is pulled forward and to thereby disalign the toothed wheels B' from the notched disks 110 A'. When the hand lever returns, the cam hook shifts the shaft back again and re-aligns said toothed wheels with said disks.

The shaft 60^x of the rear controlling devices is embraced by a slotted link 62 whose 115 forward portion has a cam formation corresponding with that of the hook 61. This link is pivotally connected with the stud 50^a of the crank arm 50 which couples that arm with the lever 51, and so will be reciprocated whenever the hand lever is operated for 120 zeroizing the rear accumulator. The link 62 is preferably guided in its reciprocations by a horizontal slot z' in the right hand frame-piece of the machine, the link having 125 a stud 62^a occupying said slot.

The machine as I have here shown it has only two rows of numbered keys, but it will of course be understood that in practice there would ordinarily be a very much 130

greater number of rows of keys and corresponding trains of mechanism.

It will be obvious that the above described machine is well calculated to subserve the purposes outlined in the opening statement of this specification. With the "duplex" key 38 up, the machine can manifestly serve as a key-driven calculator of single accumulation capacity, after the manner of the well-known prior machines. With said key down, simultaneous registration in the two accumulators can be practised. With the other special key 53 up, the front accumulator can be zeroized while the total of preceding registrations is preserved upon the rear accumulator. Then a second series of amounts can be accumulated upon the forward accumulator and simultaneously added to the accumulation upon the rear accumulator. Finally, when the calculation is completed, both the accumulators can be zeroized by depressing the said key 53 and pulling the zeroizing handle.

While, as above stated, the machine constructed in the manner above described, is well calculated to subserve these purposes, it must be understood that the invention is susceptible of embodiment otherwise than as here shown.

30 I claim:

1. The combination of vibrating register actuators; keys which differentially impart movement to said actuators; a plurality of sets of adding wheels, each set having its own carrying mechanism; driving connections between the actuators and said sets of wheels; with settable provisions for causing simultaneous registration of amounts upon both sets of wheels, or upon one set independently of the other, by the power imparted through the keys; a zeroizing handle; and separable connections between the same and the sets of wheels for either simultaneously turning the sets of wheels to zero or turning one set only to zero.

2. The combination of vibrating actuators; keys for differentially driving the same; a set of registering wheels; mechanism driven by the actuators for turning said wheels; carrying mechanism connecting the wheels; a second set of registering wheels; mechanism for driving them; means

for directly connecting said mechanism with and disconnecting it from the actuators; carrying mechanism connecting the wheels of the said second set; zeroizing mechanism for each set of wheels comprising means for collectively advancing them independently of the actuators and utilizing the carrying mechanisms; an actuator operatively connected with the zeroizing mechanism of the first mentioned set of wheels; and means for coupling said actuator to and uncoupling it from the zeroizing mechanism of the second set of wheels.

3. The combination of vibrating actuators; keys for differentially driving the same; a set of registering wheels; mechanism driven by the actuators for turning said wheels; carrying mechanism connecting the wheels; a second set of registering wheels; mechanism for driving them, including vibrating members located adjacent the actuators and having movably mounted couplers to engage the same; a key and connections for controlling said couplers; and carrying mechanism connecting the wheels of said second set.

4. The combination of vibrating actuators; keys for differentially driving the same; a set of registering wheels; mechanism driven by the actuators for turning said wheels; carrying mechanism connecting the wheels; a second set of registering wheels; mechanism for driving them; means for directly connecting said mechanism with and disconnecting it from the actuators; carrying mechanism connecting the wheels of the said second set; zeroizing mechanism for each set of wheels comprising means for collectively advancing them independently of the actuators and utilizing the carrying mechanisms; a vibrating actuator operatively connected with the zeroizing mechanism of the first-mentioned set of wheels; a link operatively connected with the zeroizing mechanism of the second set of wheels and engageable with and disengageable from said vibrating actuator; and a key and connections controlling said link.
